UNITED STATES PATENT OFFICE.

POLYDORE DORGEVAL, OF PATERSON, NEW JERSEY.

POWER-LOOM.

SPECIFICATION forming part of Letters Patent No. 234,758, dated November 23, 1880.

Application filed April 30, 1880. (No model.)

To all whom it may concern:

Be it known that I, POLYDORE DORGEVAL, of Paterson, in the county of Passaic and State of New Jersey, have invented a new and useful Improvement in Power-Looms; and I do hereby declare that the following is a full, clear, and exact description of the same.

The object of my invention is to fit looms for being driven by power for weaving classes of goods heretofore woven on hand-looms, and to provide an automatic device for tightening the filling at the end of the pick.

My invention consists—

First, in a lay or batten constructed in two portions, one portion consisting of the shuttle-rail supported on arms that are vibrated by power, the other portion consisting of the reed carried by side arms hung on a shaft, which arms are moved to beat up by a weight. The reed-frame is behind the shuttle-rail, so that the backward movement of the reed is given by contact of the shuttle-rail.

Second, in a cam-and-link connection of peculiar construction for vibrating the batten and resting the same to give time for the passage of the shuttle.

Third, in fingers pivoted on the shuttle-rail and connected with slide-blocks in the shuttle-boxes, for movement by the shuttle to raise and hold the weft-thread taut during the movement of the batten.

Fourth, in a brake operated by an arm on the shuttle-rail, for stopping the loom in case the shuttle stops short of its box.

These features will be more particularly described hereinafter, with reference to the accompanying drawings, forming part of this specification, wherein—

Figure 1 is a side elevation of my improved loom, the heddles and warp-beam and their operating mechanism being omitted. Fig. 2 is a vertical transverse section. Fig. 3 is a vertical longitudinal section on line *yy* of Fig. 2. Fig. 4 is a plan view, showing the cloth-beam and finishing-roll, the breast-beam being removed. Figs. 5 and 6 are side elevations of the frame of a loom, showing such parts only of the machine as are required to illustrate the operation of a portion of the brake and stop mechanism. Fig. 7 is a detail, in elevation, of a portion of the said brake and stop mechanism;

Fig. 8, a detail plan view, showing the operation of the device for holding the weft-thread taut during the movement of the batten; and Fig. 9 is a perspective view of a portion of the 55 brake and stop mechanism with a portion of the frame shown broken away.

A is the frame of the loom; *a*, the breast-beam; and *b* the cloth beam or roller. *c* is a shaft fitted in suitable bearings beneath the 60 beam, and carrying at its end the pulleys *d* that operate the lay, as hereinafter described. This shaft *c* may be driven by hand or by a belt, *c'*, that passes around a pulley, *c''*, on the shaft *c*, and a pulley, *a''*, upon a driving-shaft, 65 *a''*, secured by bearings to the lower and rear part of the frame.

e is a shaft fitted in suitable bearings at the back and lower part of frame *A*. Upon this shaft, near its outer ends, are fitted the arms 70 or swords *ff*, that carry the shuttle-rail *g* and boxes *B*, and also the arms *h h*, that are loose on the shaft and carry the reed-bars *i i*, in which the dents of the reed are secured by any desired means. From the hubs of the 75 arms *h* on shaft *e* extend weighted arms *k*, which tend to throw the arms *h* and reed forward and maintain contact between the lower reed-bars, *i*, and shuttle-rail *g*.

From the arms *f* rods *l l* extend forward 80 and are connected to the slotted cam-pieces *m*, which are hung at opposite ends of the loom by the arms *n n*, that are pivoted at the lower part of frame *A*. Upon the pulleys *d* are crank-pins *d'* which enter the slotted cams *m*. 85 The slots of the cams *m* extend above and below the center of pulleys *d*, so that by the revolution of the pulleys *d* the cam-pieces *m* and arms *f* are vibrated back and forth.

The slots of the arms *m* are so shaped as to 90 operate the batten as follows: first, to cause the recoil of the batten with a medium rapidity; second, at the end of the course to give a dead-point or rest to permit the shuttle to pass, and third, to cause the return movement to be made 95 with great rapidity to permit the reed to be carried against the fell or edges of the cloth being woven with proper force by the action of the weighted arms. The shape of the slots *m* may be particularly described as having a 100 concentric central portion and an outwardly curved or tangential end portion. By this

construction the shuttle-race is moved forward by the power, and is followed up by the reed by the action of the weighted arms *k*, and both the shuttle-rail and reed are moved back by power. The reed thus beats up the filling with a light stroke, which may be regulated by adjustment of the weights *k'* on arms *k* by means of set-screws *k''*, whereby the weights *k'* may be secured at any desired position upon the arms to increase or decrease the effect of their weight. At the backward movement the shuttle-rail and reed-bars are in contact, and the shuttle will be thrown by any usual means at the pause in the movement.

15 The shaft *c*, as shown in Figs. 3 and 4, is fitted with a spiral blade, *c'*. The cloth in passing from the beam *a* to the roller *b* passes at the back of roller *c* in contact with the blade *c'*, and by the revolution of shaft *c* the blade 20 is caused to rub upon the face of the cloth to smooth and finish the surface.

Upon the front of the shuttle-rail *g*, at each end, a finger, *o*, is pivoted, from which finger a rod, *p*, extends to and is connected with a 25 lever, *q*, that is hung on the front of rail *g*. The upper end of lever *q* is bent back above the shuttle-box *B*, as shown in Fig. 1. In the box *B* is fitted a loose slide-block, *r*, and connected with the lower end of lever *q* is a spring, 30 *q'*, that tends to throw the finger *o* down below the upper edge of the rail *g*. As the shuttle enters the box it strikes the block *r*, moves it back, and thus moves the lever *q* and raises the finger *o*. The finger *o* in this position will 35 come in contact with the weft as the reed moves forward, taking up the slack in advance of the reed and holding the weft taut until the shed has changed, after which, the shuttle being shot and the block *r* thus relieved, the 40 spring *q'* will instantly carry the fingers *o* down out of the way of the shuttle. The finger *o* rises after the shuttle has passed and entered its box, and then as the lay goes forward the finger passes upon the filling-thread and 45 carries the thread forward. This takes up the slack, and the thread is held tightly as the reed beats up, thereby insuring a tight selvage.

The blocks *r* are also used to throw the stop-motion out of action when the shuttles enter 50 the boxes, and allow the same to act if the shuttles fail to enter. A lever, *s*, hung beneath each box, *B*, is connected by one end to block *r*, and carries at the other end a rod, *t*, that slides in a lug or flange on the rod *l* of the vibrating arm *f*. Between the arms *f*, and pivoted in said arms, is a cross bar or rod, *u*, having projections *w'*, Fig. 1, which extend toward the arms *v* of the brakes *v'*, that are pivoted at *v''* on frame *A*, to bear on the periphery of the pulleys *d*. The rod *u* also carries arms *w*, which are above the slide-rods *t*. At the forward movement of arms *f* the projections *w'* will come in contact with the brake-arms to brake the pulleys except when the rod 65 *u* is moved or held by the rods *t* passing beneath the arms *w*, as shown in Fig. 7. This

forward movement of rods *t* is accomplished by contact of the shuttle with block *r* as the shuttle enters the box, so that as the lay goes forward the swinging movement of the rods *l* will raise the rods *t* and arms *w*, and the projections *w'* will pass above the brake-arms without effect. The rod *u* and its arms and projections are restored to their operative positions after the rod *t* is withdrawn by the weight of the said arms and projections, which are all arranged upon the same side of its axis, and the strength of the spring *t'* is sufficient to hold the rod *t* out of action.

It will thus appear that the projections *w'* are held up by rods *t* at each end of the lay acting alternately upon the arms *w* of the shaft *u*. The rods *t* are withdrawn as the shuttle is thrown by the spiral springs *t'*.

The brake-arms *v* will be connected to suitable devices for throwing off the power at the same time the brake is applied, and it will be seen that in case the shuttle fails to enter the box the stop-motion will remain operative.

The mechanism for throwing off the power 90 at the same time the brake is applied is as follows: *a'* *a''* are the loose and fast pulleys on the driving-shaft *a*. *b'* is the belt-shifter, fitted on frame *A*, to which is also fitted the cross-shaft *e'*, that extends from the front to the back 95 of said frame, and has an arm, *e''*, at the back that connects with the belt-shifter *b'*, and a crank-arm, *e''*, at the front that connects with the spring-lever *f'*. The spring of lever *f'* tends to move the belt-shifter and throw the 100 belt on the loose pulley. The upper end of the lever *f'* passes through a guide, *g'*, having an L-slot, on which guide is pivoted a lever, *h'*. One arm of said lever *h'* is connected to the brake-arm *v* by rod *h''*, while the other extends at the side of lever *f'*. The lever *f'* is moved by hand to shift the belt to fast pulley, and then caught upon the shoulder *g''* of the L-slot to prevent its return. The movement 105 of brake-arm *v* to brake-wheel *d*, as before described, causes lever *h'* to disconnect lever *f'* from the shoulder *g''* by pressing against it, so that the spring of the latter is free to act. The rod *u* is provided with projections *w'* on both sides of the loom for operating the brake-arms *v*, so that the stop-motion is brought into 110 action from either side of the loom.

By the construction described the loom is adapted for weaving by power any kind of rich or common goods. In weaving common 115 goods, such as are usually woven by power, the two-part batteau may be connected together by suitable fastenings.

Having thus described my invention, what I claim as new is—

1. In looms for weaving, the double lay or battens, consisting of the arms *f*, and shaft *e*, the shuttle-rail *g* carried thereby, the driving-shaft provided with positive connections with the rail, in combination with the arms *h*, pivoted to the shaft *e*, independently of arms *f*, the weighted arms, and the reed secured to

the arms *h*, and operated upon to receive the backward movement by the pressure of the shuttle-rail and its forward movement by the weights, substantially as described.

5 2. In combination with the pivoted arms *f* and shuttle-rail *g* and vibrating arms *h*, carrying the reed, the rods *l*, slotted and pivoted cam-pieces *m*, pulleys *d*, provided with pins *d'*, and driving-shaft *c*, for vibrating the arms *f*, these parts being constructed, combined, and arranged to operate substantially as specified.

3. In looms for weaving, the pivoted fingers *o*, rods *p*, levers *q*, and slide-blocks *r*, combined

with the shuttle rail and boxes, substantially as described, for operation as specified.

4. In a loom, the combination of the shaft *c*, the pulleys *d*, the brake-arms *v*, the rod *u*, the arms *f*, and the batten vibrated by suitable connections from shaft *c*, the projections *u'* on rod *u*, and the arms *w*, with the slide-rods *t*, 20 levers *s*, slide-blocks *r*, and the shuttle-boxes, substantially as and for the purpose described.
